UNITED STATES PATENT OFFICE.

JAMES McKECHNIE, OF BARROW-IN-FURNESS, AND BARNES NEVILLE WALLIS, OF KENTS BANK, ENGLAND, ASSIGNORS TO VICKERS LIMITED, OF WESTMINSTER, LONDON, ENGLAND.

MACHINE FOR DRILLING OR PUNCHING HOLES FOR RIVETS.

1,320,159.

Specification of Letters Patent.

Patented Oct. 28, 1919.

Application filed March 27, 1919. Serial No. 285,616.

To all whom it may concern:

Be it known that we, Sir JAMES McKECHNIE, K. B. E., and BARNES NEVILLE WALLIS, both subjects of the King of Great Britain, residing, respectively, at Naval Construction Works, Barrow-in-Furness, in the county of Lancaster, England, and 3 Kentsford Terrace, Kents Bank, Grange-over-Sands, in the county of Lancaster, England, have invented certain new and useful Improvements in or Relating to Machines for Drilling or Punching Holes for Rivets or the like, of which the following is a specification.

This invention relates to machines for drilling or punching holes for rivets or the like in bars or members of channel, angle or other section used in connection with light braced girders or other structural work, the said machines being of the kind in which the bars or members to be operated upon are fed intermittently through the machine in steps of the required degree to accord with the pitch of the holes to be drilled or punched.

According to this invention, the bar or other member to be drilled or punched is fed through the machine by appropriate devices controlled by a rotatable power driven pitch plate having teeth or projections spaced apart in accordance with the desired pitch of the holes to be drilled or punched and adapted to coöperate with a stop or trip device which normally engages with one or other of said projecting elements on the pitch plate to prevent rotation of said pitch plate and operation of the work-feeding means, there also being provided means for disengaging said trip device thereby enabling the pitch plate to be driven and the work feeding means to become operative.

In order that the said invention may be clearly understood and readily carried into effect the same will now be described more fully with reference to the accompanying drawings which illustrate one form of drilling machine embodying our invention and in which—

Figure 1 is an elevation and Fig. 2 a plan of the machine.

Fig. 3 and 4 are elevations taken at right angles to Fig. 1 looking in the direction of the arrows A and B, respectively.

Fig. 5 is a detail view showing in eleva-

tion means for limiting the extent to which the bar or member to be drilled can be initially introduced into the machine.

Fig. 6 is a fragmental plan view thereof.

Fig. 7 is a sectional plan view of the pitch controlling mechanism.

Fig. 8 is a sectional elevation of power driven frictional gearing which operates in conjunction with the pitch controlling mechanism.

Fig. 9 is a sectional detail view showing devices for automatically rendering the pitch controlling mechanism operative.

Figs. 10, 10^a, 10^b, and 10^c are detail views showing devices for automatically controlling the drill feeding mechanism.

Fig. 11 is a fragmental elevation taken at right angles to Fig. 10, and

Fig. 12 is a sectional detail view showing one of the drills and relative parts.

a denotes the bar which is to be bored, the said bar in the example shown being of channel formation in cross section and being guided between a feed roller *b* and a pressure roller *c*. The pressure roller is yieldably maintained in engagement with the bar during the feed movement by a pivoted lever *d* (Figs. 1, 4 and 5) having a spring *e* associated therewith and connected to arms *f* for supporting the pressure roller, the said lever being actuated against the resistance of the said spring through the medium of a projection or cam *g* which participates in the movement of a handle *h*, whereby the pressure roller *c* can be raised by the machine attendant to allow the bar *a* to be introduced between it and the feed roller *b* (see Fig. 5).

In order to insure that the bar shall only be initially fed forward by the operator to an extent corresponding to the distance of the front end of the bar from the first hole to be drilled, we provide the stop device which is shown more particularly by Figs. 5 and 6 and which comprises a member *i* having transverse pins *i*^x, with which the front end of the bar normally makes contact. The said member *i* of the stop device is shown adjustably mounted on a slotted link *j* extending longitudinally of the machine and connected at its ends to pivoted parallel arms *k* and *l*, the arm *k* being movable with the aforesaid handle *h* and cam *g* and the arm *l* being provided with a notch

or recess m (Fig. 5) normally engaged by a catch constituted by one arm n of a bell-crank lever (Figs. 2 and 3) the other arm o of which is adapted to be actuated at the proper time by a pin or projection p (Figs. 2, 3 and 7) on the pitch plate hereinafter referred to, so as to disengage the said arm n from the recess m whereupon the arms k, l are free to move angularly in the direction 10 of the arrow (Fig. 5.) When the handle h is now actuated by the machine attendant the stop device will be lowered out of the path of movement of the bar and the cam g will also be moved simultaneously out of 15 contact with the lever d . The latter then operates under the action of the spring e to bring the pressure roller c into engagement with the bar a with the result that the said bar will then be moved forward by the feed 20 roller b , when the latter is set into motion by the release of the pitch plate as herein-after described.

The aforesaid pitch plate comprises in the example illustrated a rotatable casing (Fig. 7) having annular flanges q, r and s , the flange r being provided with the aforesaid pin or projection p and the flange s being provided with detachable and adjustable teeth or projections t which are secured in 30 position by means of bolts u and are adapted to be engaged by a stop device. By setting the said teeth or projections at appropriate distances apart any desired predetermined pitch of the holes to be drilled can be obtained, owing to the fact that the movement 35 of the feed roller b is continuous while the pitch plate is moving through the angular distance between any two of the different teeth or projections; thus the degree of the feed movement imparted to the bar is capable 40 of variation to accord with the desired pitch of the holes, by altering the setting of the said teeth or projections. The said stop device comprises in the example shown a spring bolt v (Fig. 9) normally projecting from a 45 supporting box w and adapted to engage with the teeth or projections t and to be released therefrom by automatic means. For this purpose a resilient pawl x is mounted 50 on a pivoted lever y and arranged to cooperate with a relatively fixed cam z so that when the said lever y is actuated in the direction of the arrow in Fig. 9 the pawl x first operates to withdraw the spring bolt 55 and then suddenly release it so that it resumes its stopping position under the action of the spring a' before the next tooth or projection on the pitch plate arrives adjacent to it. The said cam z is capable of adjustment relatively to the lever y so that the pawl x can be caused to become disengaged from the spring bolt v at an earlier or a 60 later period, in the stroke of the lever y according to requirements. The said pitch plate is rotated through the medium of

power driven frictional gearing which however only becomes operative when the aforesaid spring bolt v is disengaged from the pitch plate. The said frictional gearing comprises in the example shown a power driven pulley b' (Figs. 2, 4 and 8) provided with a bush c' freely mounted on a shaft a''' , the ends of the boss of the pulley being maintained by means of a spring d' in frictional engagement with facings e' of leather, fiber or other appropriate material provided on flanged collars f', g' , the collar f' being slidably mounted on the shaft a''' and acted upon by the spring d' the initial pressure of which can be varied when required by 75 means of an adjustable collar h' . By means of the aforesaid friction collar f' and its spring, the pulley b' although kept constantly running, will only operate to drive the pitch plate when the spring bolt is disengaged from the teeth or projections t thereof. The shaft a''' is provided with a coupling member $a''*$ for engagement with a corresponding member on a helical gear wheel i' keyed to the shaft carrying the feed roller b , so that when the spring bolt v is disengaged as aforesaid, the shaft a''' will drive the feed roller b , and, through the medium of the helical gear wheels j', i' , the shaft h' and toothed wheels l', m' and n' also 90 impart rotary movement to the pitch plate. The said pitch plate is provided with an internal gear wheel q' (Fig. 7) meshing with pinions r' in gear with a pinion o' which is driven from the pinion n' . The said pinions r' are carried by a disk s' secured to a shaft t' in axial alinement with the shaft p' , the pitch plate being freely mounted relatively to the said shafts. The intermediate gearing m' may comprise change 95 wheels for the purpose of varying the extent of the intermittent movement to suit the pitch required. Striker pegs u' , the number and disposition of which can be varied as required, are provided on the annular flange q of the pitch plate, and a worm wheel v' on the shaft t' , gears with a worm w' (Fig. 7) which is adapted to be operated in one direction or the other through the medium of a clutch x' and bevel gearing y' 110 operated by a star wheel z' secured to a shaft a^2 and actuated to the desired extent by the said striker pegs. With this arrangement, when the spring bolt v is disengaged from the pitch plate the latter in moving 115 from one pitch tooth or projection to another transmits through the medium of the striker pegs u' and the star wheel z' a variable amount of rotation (in accordance with the number of pegs successively actuating the star wheel) in one direction or the other, to the shaft t' which in turn imparts (through the medium of the pinions r' acting in conjunction with the internal gear wheel q' and the pinion o') a corresponding 120 125 130

amount of rotation in one direction or the other to the shaft p' against the resistance of the power driven frictional gearing associated with the feed roller b ; thereby enabling if necessary the extent of intermittent movement of the bar a to be modified in fine increments or decrements of adjustment at each pitch movement, in accordance with the setting of the clutch x' . In the 10 position of the clutch shown in the drawing no modification of the intermittent movement of the bar will occur although the star wheel z' will be actuated by the striker pegs u' . Alternatively, the desired fine adjustment of the pitch may be obtained by 15 transmitting movement from the shaft t' to the shaft p' through the medium of manually controlled devices, the pitch plate being restrained against movement during adjustment, by means of the spring bolt v .

The holes in the bar a may be formed by one or more drilling machines arranged so that the drilling operation may be carried out at one side of the bar or at both 20 sides thereof, as required. As shown in Figs. 2 and 4, two drilling machines are employed (one arranged to operate on each side of the bar) each drilling machine being mounted on a bracket c^2 so as to be capable of adjustment relatively thereto. The said bracket c^2 is also adapted to be adjusted vertically on guides d^2 provided on a standard or bracket e^2 (Figs. 1, 2 and 4) which in turn is adapted to be adjusted longitudinally on 25 guides provided on a transversely adjustable bed portion f^2 secured to the base g^2 of the machine. In the example shown, the drilling machines are interconnected in such a manner that both of the drills are actuated simultaneously. The drill spindles h^2 are each conveniently rotated by means of a power driven belt pulley j^2 (Figs. 1, 2 and 4). For controlling the feeding and return movements of the said drill spindles any 30 appropriate arrangement may be adopted; in the example illustrated there is a shaft j^2 (Figs. 1, 2, 3 and 10^a) which is mounted in bearings j^{2x} and receives intermittent rotary motion *i.e.* one revolution at a time from 35 a power driven belt pulley j^0 as hereinafter described, the said shaft being provided with a crank disk k^2 . This crank disk has an adjustable crank pin (Figs. 10^a and 10^b) which is connected by means of a rod l^2 to 40 an arm m^2 secured to a shaft n^2 which at each revolution of the crank disk k^2 is rocked about its axis for half a revolution in a forward direction and half a revolution in a backward direction thus causing the drills 45 of the drilling machines to be advanced and drill the holes in the bar and then to be retracted as will be readily understood from the ensuing description. The said shaft n^2 imparts its rocking movements to a transverse shaft p^2 through bevel gearing o^2 (see

Fig. 2) the said shaft p^2 being provided with helical gear wheels q^2 meshing with helical gear wheels r^2 on longitudinal shafts s^2 which by means of bevel gearing t^2 operate vertical shafts u^2 . These shafts u^2 in 70 turn actuate bevel gearing v^2 and thus impart movement to shafts w^2 each of which is provided with a pinion x^2 in gear with a rack y^2 (Fig. 12) formed on a sleeve z^2 surrounding the corresponding drill spindle 75 h^2 and movable axially therewith.

The said sleeve is shown provided with a cylindrical enlargement a^3 for the reception of the inner end of a hollow member b^3 having a pin and slot connection therewith, the 80 outwardly projecting portion c^3 of the said hollow member being of conical formation and having secured thereto at its outer extremity a bush d^3 through which the drill passes as shown in Fig. 12, the said member 85 b^3 being adapted to bear resiliently against the bar a through the medium of a spring e^3 and serving in conjunction with a hook-like element f^3 to steady the drill during the drilling operation and also to facilitate the 90 guiding of the bar a when the latter is being fed through the machine. The said element f^3 is pivotally connected by means of a bolt or pin g^3 to a rod h^3 adjustably secured to a relatively fixed part i^3 of the drilling machine, and has a pin and slot connection with an arm j^3 extending upward from the part c^3 of the member b^3 , for the purpose of enabling the said element f^3 to be 95 adjusted if required, through the medium 100 of the rod h^3 .

The aforesaid shaft n^2 (Fig. 2) receives its rocking movement by means of clutch mechanism (Figs. 1, 2, 10^a and 10^b) comprising an axially movable member k^3 having a feather key and groove connection with the said shaft j^2 and provided with teeth k^{3x} adapted to engage against the power of a spring q^3 with yieldable teeth l^{3x} (of which one only is shown) pivotally mounted on a 105 member l^3 forming part of the belt pulley j^0 . The clutch member k^3 has a face cam m^3 (see Figs. 10^a and 10^b) and engages with a bell crank lever n^3 for moving the said member k^3 toward the driving member l^3 , the arrangement being such that the bell crank lever n^3 only effects a slight initial movement of the member k^3 toward the member l^3 , the full engagement of the two members being effected by the cam m^3 coöperating 110 with a roller o^3 on a fixed bracket p^3 . The said cam is of such form that at each revolution of the shaft j^2 the clutch member k^3 is disengaged from the member l^3 by means of the spring q^3 acting upon the said member 115 k^3 , thus rendering the shaft j^2 inoperative although the belt pulley j^0 still continues to be driven.

The said clutch mechanism is automatically controlled from the aforesaid pitch 120 125 130

plate, and in the example illustrated this is effected by the projecting nuts u^x of the bolts u (Figs. 2 and 7) actuating a lever r^3 (Figs. 2, 3 and 10) toward the end of the pitch movement. This lever extends at its upper end through an opening in the base g^2 and at its lower end is connected by means of a rod e^3 to a bell crank lever t^3 engaging a slot in a rod u^3 connected to the bell crank lever n^3 which controls the clutch member k^3 of the drill control mechanism. When the parts are in the normal position shown the bell crank lever t^3 is engaged at the shoulder v^{30} thereof by a pivoted trip lever v^3 . The movement transmitted by the rod s^3 to the bell crank lever t^3 is imparted to the rod u^3 and bell crank lever n^3 thereby causing initial engagement of the clutch members k^3 , l^3 to take place, the part v^3 of the trip lever having been simultaneously released from the shoulder v^{30} and, under the action of the spring v^{31} , co-operating with the part x^3 of the bell crank lever t^3 so as to cause the clutch members k^3 , l^3 to be maintained in engagement with one another, until the cam portion m^3 of the clutch member k^3 co-operates with the roller o^3 aforesaid and causes the clutch members k^3 , l^3 to be fully engaged and the drilling operation to be effected, after which the clutch member k^3 is disengaged from the clutch member l^3 under the action of the spring q^3 and the shaft j^2 comes to rest, the trip lever v^3 having previously been returned to its normal position by means of the lower end of the rod u^3 making contact with a pin u^{33} during the axial movement of the clutch member k^3 under the action of the cam m^3 and the bell crank n^3 , the bell crank t^3 being simultaneously returned to its normal position by the spring y^3 (Fig. 10). The shaft j^2 is provided with the cam z^3 (Figs. 1, 2, 3 and 9) which is so formed that when the drilling operation has been effected and the drill withdrawn from the bar a , the aforesaid spring bolt v is disengaged automatically from the pitch plate in order to enable the bar a to be fed forward in accordance with the desired pitch. For this purpose, the aforesaid lever y on which is mounted the pawl for co-operating with the spring bolt v , is inter-connected by means of a link a^4 (Fig. 9), with a lever b^4 adapted to be operated by the said cam z^3 against the action of a spring c^4 . It will thus be seen that the drilling control mechanism is interconnected with the pitch plate through the cam z^3 on the shaft j^2 and the intervening parts for actuating the spring bolt v and that the pitch plate is interconnected with the drilling control mechanism through the lever r^3 and intervening parts for actuating the bell-crank lever n^3 and the clutch member k^3 so that at each disengagement of the spring bolt

from the pitch plate the latter effects a feeding forward of the bar under treatment for one step and that as the latter comes to rest the drilling control mechanism becomes operative by the movement of the clutch member k^3 and after performing its function comes to rest again just after the cam z^3 has caused the spring bolt to be disengaged from the pitch plate for enabling the latter to effect a further feeding movement of the bar. The pitch plate and the drilling control mechanism thus come into operation alternately and each is dependent upon the other for determining the period at which it will start and stop; there can thus be no chance of the feeding of the bar and the drilling thereof occurring out of proper sequence.

A contrivance may also be provided whereby the clutch devices controlling the aforesaid drill feeding mechanism are automatically rendered inoperative in the event of the tail or rear end of the bar passing a predetermined point after the required number of holes have been drilled. For this purpose, the said contrivance may comprise a lever d^4 (Figs. 1 and 2), pivotally mounted on a longitudinally adjustable support e^4 carried by a guide bracket f^4 secured to the base g^2 . One end of the lever d^4 is provided with a roller or pin f^{40} resting normally upon the bar a , and the other end which is preferably made adjustable is provided with a roller g^4 for co-operating with a pivoted stop element h^4 provided contiguous to the upper end of a lever i^4 pivotally mounted on the support e^4 and adjustably connected at its lower end to a rod or link j^4 extending longitudinally of the machine and connected at its forward end to a pivoted arm k^4 (Figs. 1, 3, 10, 11) provided with a part l^4 of arcuate form. With this arrangement, when the tail or rear end of the bar a clears the pin f^{40} the lever d^4 moves about its pivot in the direction of the arrow m^4 (Fig. 1) whereupon the roller g^4 is moved out of contact with the pivoted stop element h^4 on the lever i^4 , which lever is then moved about its pivot in the direction of the arrow n^4 by means of the spring o^4 , thereby actuating the arm k^4 and causing the arcuate portion l^4 to become disposed in the path of movement of an extension v^{33} of the trip lever v^3 (see Figs. 3, 10 and 11). The trip lever is thus prevented from being moved upward to co-operate with the bell crank lever t^3 as aforesaid, any tendency of this bell crank lever to cause the clutch member k^3 to become engaged with the driving clutch member l^3 , being immediately counteracted by the spring q^3 acting upon the said member k^3 , the cam m^3 being so constructed as to enable this to be effected. The bell crank lever t^3 is shown provided with a handle p^4 (Figs. 1, 3 and 10) extending outward

through a slot in the side of the base g^2 whereby the machine attendant can render the clutch mechanism operative when a bar has been placed in the machine and it is desired to start the drilling of the holes therein.

- In the operation of the machine, the bar to be drilled is placed in the machine so that the front end thereof makes contact with the pins i^* of the stop device (Figs. 1, 2, 5 and 6) which regulates the distance of the first hole or holes from the front end of the bar, the spring bolt v engaging at such time with one of the teeth or projections t on the pitch plate 10 to prevent rotation thereof. The machine attendant then actuates the handle p^4 (Figs. 3 and 10) and thereby causes the clutch members k^3, l^3 to engage whereby the crank disk k^2 (Figs. 1, 2 and 3) is rotated a single 15 revolution and during one half revolution thereof effects through the medium of the arm m^2 and intervening gearing the feeding movement of the drill spindles h^2 which are rotated by means of the belt driven 20 pulleys i^2 and thus drill the holes in the bar. The return movement of the drill spindles after performing the drilling operation is obtained by a reversal of the direction of rotation of the said gearing which 25 takes place during the other half revolution of the crank disk. Toward the termination of the return movement of the drill spindles, the cam z^3 (Figs. 1, 2, 3 and 9) actuates the lever b^4 thereby causing the 30 pawl x (Figs. 3 and 9) to withdraw the spring bolt v from engagement with the said tooth or projection t on the pitch plate. The said pitch plate is thus free to be actuated from the power driven pulley b' through 35 the frictional gearing and interposed shafts $a''' k'$ and gear wheel associated therewith. Meanwhile the clutch member k^3, l^3 are disengaged by means of the spring q^3 (Fig. 7) as aforesaid, to render the crank disk k^2 40 inoperative, and the projection p (Figs. 2, 3 and 7) on the pitch plate comes into contact with the arm o of the bell crank lever n, o so as to disengage the arm n from the recess in the lever l and enable the stop device to be moved out of the path of movement of the bar which is then fed forward by the pressure and feed rollers through the intervention of the aforesaid frictional gearing. This forward feed of the bar continues 50 until the spring bolt v which promptly returns to its normal position after each actuation thereof by the pawl x as aforesaid, stops further movement of the pitch plate by the next tooth or projection t thereon. 55 on engaging with the said spring bolt whereupon the feeding movement of the bar ceases and the drills are brought into operation to drill the next holes, the clutch mechanism controlling the disk k^2 being initially 60 rendered operative through the medium of

the lever r^3 and bell crank lever t^3 interconnected therewith, the lever r^3 being actuated by the nut u^* of the said next tooth or projection t prior to the latter being engaged by the spring bolt. After this drilling operation has been performed, the cam z^3 again comes into action to withdraw the spring bolt as aforesaid and permit the pitch plate to be set in motion and the bar to be fed forward to the next position in which the holes are to be drilled, the pitch plate in turn controlling the actuating of the drills and so on until the required number of holes have been drilled. As the bar is moved forward by the pressure and feed rollers after the final drilling operations the tail or rear end thereof will become disengaged from the roller or pin f^{40} (Figs. 1 and 2) and the lever d^4 will be moved about its pivot in the direction of the arrow m^4 and the other roller g^4 moved 80 cut of contact with the stop element h^4 on the lever i^4 . The latter therefore will be moved about its pivot in the direction of the arrow n^4 by means of the spring o^4 and rod j^4 whereupon the arm k^4 (Figs. 1, 3, 10 and 11) is actuated and causes the arcuate portion l^4 thereof to come into the path of movement of the extensions v^{33} of the trip lever v^3 and thus prevent the drilling control mechanism from becoming operative. 95

The mechanism for enabling the extent of intermittent movement of the bar to be modified as aforesaid, is only rendered operative through the medium of the striker pegs u' , star wheel z' and clutch x' , when 100 it is desired to obtain fine increments or decrements of adjustment at each pitch movement, the clutch x' being normally in the neutral position shown in Figs. 2 and 7.

It will be understood that while the embodiment hereinbefore described provides only for the drilling of the holes in the bar, the machine may be readily adapted to punch the said holes. The machine may also be varied in many respects, for instance, the aforesaid pressure and feed rolls may be dispensed with, in which event an intermittently operated endless chain or chains or similar devices provided with feed dogs and acting in conjunction with the pitch 110 plate and the aforesaid stop or trip device may be employed for the purpose of supporting the bar and feeding it through the machine in accordance with the desired pitch of the holes to be drilled or punched. It will 115 also be understood that instead of the pitch plate being controlled automatically as above described it may be controlled manually in which case the disengagement of the aforesaid spring bolt from the pitch plate would 120 be effected by a hand lever or pedal suitably connected therewith.

What we claim and desire to secure by Letters Patent of the United States is:—

1. In a drilling or punching machine, the 130

- combination with means for feeding the work through the machine, of a rotatable power driven pitch plate interconnected with the work feeding means and having 5 projecting elements spaced apart in accordance with the desired pitch of the holes to be drilled or punched, a trip device normally engaging with one or other of said projecting elements on the pitch plate to prevent 10 rotation of said pitch plate and operation of the work feeding means, and means for disengaging said trip device and enabling the pitch plate to be driven and the work feeding means to become operative.
- 15 2. In a drilling or punching machine, the combination with means for feeding the work through the machine, of a rotatable power driven pitch plate interconnected with the work feeding means and having 20 projecting elements spaced apart in accordance with the desired pitch of the holes to be drilled or punched, a trip device normally engaging with one or other of said projecting elements on the pitch plate to prevent 25 rotation of said pitch plates and operation of the work feeding means, means for disengaging said trip device and enabling the pitch plate to be driven and the work feeding means to become operative, 30 and gearing for enabling fine increments or decrements of adjustment of the work feeding means to be obtained at each pitch movement.
3. In a drilling or punching machine, the 35 combination with means for feeding the work through the machine, of a rotatable power driven pitch plate interconnected with the work feeding means and having projecting elements spaced apart in accordance 40 with the desired pitch of the holes to be drilled or punched, a trip device normally engaging with one or other of said projecting elements on the pitch plate to prevent 45 rotation of said pitch plate and operation 50 of the work feeding means, drill or punch controlling mechanism and means interconnecting the trip device with said mechanism for disengaging said trip device and enabling the pitch plate to be driven and the work feeding means to become operative when the drilling or punching operation has been effected.
4. In a drilling or punching machine, the 55 combination with means for feeding the work through the machine, of a rotatable power driven pitch plate interconnected with the work feeding means and having projecting elements spaced apart in accordance 60 with the desired pitch of the holes to be drilled or punched, a trip device normally engaging with one or other of said projecting elements on the pitch plate to prevent 65 rotation of said pitch plate and operation 70 of the work feeding means, means for disengaging said trip device and enabling the pitch plate to be driven and the work feeding means to become operative, drill or punch feeding mechanism and means interconnecting said mechanism with said pitch plate for enabling said mechanism to become operative when the work has been fed to the desired extent. 75
5. In a drilling or punching machine, the combination with means for feeding the work through the machine, of a rotatable power driven pitch plate interconnected with the work feeding means and having 80 projecting elements spaced apart in accordance with the desired pitch of the holes to be drilled or punched, a trip device normally engaging with one or other of said projecting elements on the pitch plate to prevent 85 rotation of said pitch plate and operation of the work feeding means, drill or punch controlling mechanism, means interconnecting the trip device with said mechanism for disengaging said trip device and enabling the pitch plate to be driven and the work feeding means to become operative when the drilling or punching operation has been effected, drill or punch feeding mechanism, and means interconnecting said feeding mechanism with said pitch plate for enabling said feeding mechanism to become operative when the work 90 has been fed to the desired extent. 95
6. In a drilling or punching machine, the combination with means for feeding the work through the machine, of a rotatable power driven pitch plate interconnected with the work feeding means and having 100 projecting elements spaced apart in accordance with the desired pitch of the holes to be drilled or punched, a trip device normally engaging with one or other of said projecting elements on the pitch plate to prevent 105 rotation of said pitch plate and operation of the work feeding means, drill or punch controlling mechanism, means interconnecting the trip device with said mechanism for 110 disengaging the trip device and enabling the pitch plate to be driven and the work feeding means to become operative when the drilling or punching operation has been effected, drill or punch feeding mechanism, 115 means interconnecting said feeding mechanism with said pitch plate for enabling said feeding mechanism to become operative when the work has been fed to the desired extent and gearing for enabling 120 fine increments or decrements of adjustment of the work feeding means to be obtained at each pitch movement.
